ACTUATING MECHANISM FOR PRESSING MACHINES

Filed March 16, 1926

INVENTOR.

UNITED STATES PATENT OFFICE.

ALFRED D. MAURY, OF ILION, NEW YORK, ASSIGNOR, BY MESNE ASSIGNMENTS, OF ONE-THIRD TO GAIUS A. BRAUN, OF SYRACUSE, NEW YORK.

ACTUATING MECHANISM FOR PRESSING MACHINES.

Application filed March 16, 1926. Serial No. 95,123.

This invention has for its object a particularly simple actuating and motion transmitting mechanism, which mechanism is particularly adapted for pressing machines.

5 The invention consists in the novel features and in the combinations and constructions hereinafter set forth and claimed.

In describing this invention reference is had to the accompanying drawings in which 10 like characters represent corresponding parts in all the views.

Figure 1 is a side elevation of a garment or laundry pressing machine embodying my invention.

15 Figure 2 is a detail view of the mechanism when shown in a starting position.

Figure 3 is a view similar to Figure 2 when in an intermediate position.

20 Figure 4 is a fragmentary plan view partly in section of the manual means for controlling the inlet of air into the cylinder of the air motor.

Figure 5 is a fragmentary vertical sectional view of the controlling valve.

25 Figure 6 is the fragmentary sectional view of the releasing valve.

The machine here illustrated is the conventional type of garment or laundry pressing machine and comprises a frame 1, a buck 30 2 supported by the frame, a press head 3 movable toward and from the buck 2 and carried by the forward arm of a yoke or lever 4 pivoted at 5 between its ends to a standard 6 rising from the frame and forming 35 an upward extension of the single rear leg 7 of the frame. This leg is hollow or in the form of a channel.

A counter-balancing weight 8 is mounted 40 on the rear arm of the yoke lever 4, and also the actuating mechanism is connected to such rear arm.

The actuating mechanism comprises a reciprocally movable actuator and motion transmitting means including a toggle comprising a link 9 pivoted at its upper end at 10 to the rear arm of the yoke lever 4 and at its lower end at 11 to the other link 12 of the toggle. This other link is one arm of a lever pivoted between its ends at 13 to the frame or the rear leg 8, the link 9 and the lever 12 or the upper or rear arm thereof forming the toggle. The reciprocally movable actuator is a piston rod 14 having a piston 15 movable in a cylinder 16,

the piston rod being connected to the lever 12 or the lower or front arm thereof by a link 17 which is pivotally connected at 18 to the lower end of the piston rod 14 and at 19 to the rear arm of the lever 12.

As here shown the link 17 is pivoted to a cross head or slide 20 connected to the piston rod 14 and movable along a fixed guide 21. The movement of the piston rod 14 of cross head 20 is parallel to the toggle, when straightened, formed by the link 9 and the lever 12. The guide 21 is formed integral with the rear leg 7 and is double so that the cross head engages the guide 21 at its opposite ends and the link 17 is between the guides. The cylinder 16 is suitably supported on a stud or shaft 23 located within the hollow rear leg. The throw of the piston or the extent of movement of the reciprocating actuator 14 is controlled by a suitable adjusting screw 24 adjustable to limit the downward movement of the cross head 20 and, therefore, limit the movement of the head 3 toward the buck 2. It will be understood that an adjustment of this kind is desirable for adjusting the machine to lots of work of different thicknesses.

The motive fluid for the cylinders is preferably air and is controlled by mechanism similar to that shown in Davis Patent No. 1,609,273, November 30, 1926. The air is supplied from any suitable source through a pipe 25, the flow of air being controlled to the cylinder through the intake pipe 26 by a control valve, Figure 5. This valve includes a casing 27 having a seat 28 therein and a spring pressed head 29 normally engaged with the seat 28. The valve head 29 and seat 28 are located between the feed pipe 25 and the pipe 26. The valve head 29 is mounted on a stem 29^a extending through the casing 27 to the outside thereof and operable by a lever 31, this lever being manually operable to move the valve head 29 off its seat 28 and thus permit the air to flow to the upper end of the cylinder to actuate the piston.

The air also exhausts back through this pipe 26 through the valve casing, and the stem 29^a is provided with an exhaust valve head 32 which coacts with the seat 33 when the intake valve 29 is open and is off from said seat when the intake valve is closed. Thus when the intake valve 29 is closed the

air is free to exhaust back through the pipe 26 through the valve chamber 27, past the valve head 32 and out the outlet 34.

- The intake valve 29 is held open after it has been manually operated to open position and the exhaust valve 32 held closed by back pressure operating from the cylinder through a pipe 35 leading from the cylinder into a diaphragm chamber 36 so that 5 the back air pressure acts on a diaphragm 37 in the chamber 36 which in turn acts on a sliding stem 38 coacting with an arm 39 of the lever 31 in such a manner as to cause the latter to press on the stem of the intake 10 valve 29 and hold it open. This pipe 35 communicates with the valve chamber 40 mounted on the side of the cylinder 16 near the upper end thereof, the valve member within the chamber having an operating 15 part 41 outside the chamber which part is actuated by a reciprocating rod 42.

- The valve in the casing 40 is normally closed. When the piston reaches a certain point in its out stroke, an arm 43 on the piston rod engages the shoulder 44 on the rod 42 and thus pulls on the rod to open the valve in the casing 40 permitting the pressure to pass back through the pipe 35 into the diaphragm chamber 36 and thus hold 20 the intake valve 29 open. While the intake valve is held open the pressure is held applied. To release the pressure another manually operated normally closed exhaust valve 45 is employed. The release valve 45 is located in a valve casing 46, which is connected by a pipe 47 to the diaphragm chamber 37.

- This exhaust valve 45 is spring pressed to its closed position by a spring 48 and is operated manually by a handle 49. When it is opened the air is exhausted from the diaphragm chamber 36 permitting the spring to close the intake valve 29 and open the exhaust valve 32 so that the air will exhaust 40 out of the cylinder.

- Preferably the intake valve 29 or the lever 31 thereof is operated by a two-hand operating mechanism here shown as levers 51 connected to the lever 31 through suitable 45 mechanism requiring that both levers be actuated to transmit any movement at all to the levers 31. As here illustrated the levers 51 are pivoted at 52 between their ends. One of the levers is connected by a link 53 to a toggle consisting of links 54, 55 and the other lever 51 is connected by a link 56 to a toggle consisting of the link 54 and the link 57. This link 57 is connected to the lever 31 by a link 58. Both toggles which 55 60 consists of the links 54, 55 and 54, 57 must be straightened before any effective move-

ment is transferred to the lever 31 and hence to the valve 29 thus both hands are required to permit air to enter the cylinder to close the press. Only one hand, however, is required to operate the lever 49 to open the press. 65

The levers 51 and release lever 49 are conveniently located on a support 58 on the front side of the machine. 70

What I claim is:—

1. In a pressing machine, the combination of a frame including a hollow rear leg, a buck carried by the frame, a press head movable toward and from the buck, a yoke lever pivoted between its ends to the frame and carrying the head at its front end, actuating means including a lever pivoted between its ends to the frame, a link pivoted at its upper end to the rear arm of the yoke lever and at its lower end to one arm of said lever and forming a toggle, a cylinder located in the hollow rear leg, a piston movable in the cylinder, the rear leg being formed with a guide and the piston rod having a cross-head movable along the guide, the guide extending in a general direction parallel to the toggle when the toggle is straightened and a link pivoted to said piston rod to the other arm of the lever. 80

2. A pressing machine mechanism comprising links pivoted together, one of the links being a lever pivoted between its ends, one of the arms of the lever being pivoted to the other link forming therewith a toggle, a reciprocating actuator having a cross-head thereon, a link connecting the actuator and the other arm of the lever and a guide for the cross-head, the guide being normally arranged at an angle to the lever and the lever being movable into a position in which it extends in a general direction parallel to the guide. 85

3. A pressing machine mechanism comprising links pivoted together and constituting a toggle, one of the links being one arm of a lever pivoted between its ends, a reciprocating actuating part movable in a path substantially parallel to the toggle when in straightened position, a third link 105 connecting the reciprocating part and the other arm of the lever and a guide for holding the reciprocating part in its path of movement during the rocking of the lever, the joint between the reciprocating part and the third link having means movable along 110 the guide. 115

In testimony whereof, I have hereunto signed my name at Mohawk, in the county of Herkimer, and in the State of New York, 120 this 28 day of Jan., 1926.

ALFRED D. MAURY.
